OPEN WORK PANEL.

No. 16,459.

Patented Jan. 12, 1886.

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 16,459, dated January 12, 1886.

Application filed November 13, 1885. Serial No. 182,765. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

The openings through the panel are hexagonal in form, showing two straight opposite and parallel sides, A B, and four inwardly-convex sides, D E F G. These openings appear in lateral rows at regular intervals apart. The said openings in one row alternate with the openings in the adjacent row.

Upon the face of the panel are diagonally-disposed scores I J, of lenticular shape. One of said scores, J, extends from the lower left-hand corner, for example, of the opening

marked 1 to the upper right-hand corner of the opening marked 2. The other of said scores, I, extends from the lower right-hand corner of the opening marked 1 to the upper left-hand corner of the opening marked 3. These scores are repeated between the several openings.

I claim—

The design for an open-work panel, substantially as herein shown and described, which consists of the hexagonal openings A B D E F G, appearing in rows and alternating in adjacent rows, and on the face of the panel the inclined lenticular scores I and oppositely-inclined lenticular scores J.

FREDERICK MANKEY.
